No. 11,891.

July 27- 1880.

UNITED STATES PATENT OFFICE.

DAVID McNAIR, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,891, dated July 27, 1880.

Application filed June 26, 1880. Term of patent 3½ years.

To all whom it may concern:

Be it known that I, DAVID McNAIR, of Boston, in the county of Suffolk and State of Massachusetts, have invented a new and original 5 Design for Carpets, of which the following is a specification.

The nature of my design is fully shown in the accompanying photographic illustration.

The design is composed of the larger barbaric figures A B C D, the smaller barbaric figures E F G H I J, and the angular bars or lines K, connected directly or through branches to all of said figures, so as to have the appearance of supporting them, and small conventionalized flowers and foliage thickly arranged 15 on said bars K.

I claim—

The design for carpets, substantially as shown and described.

In testimony whereof I have signed my name 20 to this specification, in the presence of two subscribing witnesses, this 24th day of June, A. D. 1880.

DAVID McNAIR.
